(57) **CLAIM**

I claim the ornamental design for a holder, as shown and described.

DESCRIPTION

FIG. 1 is a front/left/top perspective view of a holder showing my new design;

FIG. 2 is a rear/right/bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The uniformly broken lines represent portions of the holder that form no part of the claimed design; the dash-dot broken lines represent the bounds of the claimed design and form no part of the claimed design.
